P.C.(57) **CLAIM**

The ornamental design for a chair, as shown and described.

DESCRIPTION

FIG. 1 is a perspective view of a chair;

FIG. 2 is a front view of the chair of FIG. 1;

FIG. 3 is a back view of the chair of FIG. 1

FIG. 4 is a right side view of the chair of FIG. 1;

FIG. 5 is a left side view of the chair of FIG. 1;

FIG. 6 is a top view of the chair of FIG. 1; and,

FIG. 7 is a bottom view of the chair of FIG. 1.

The broken lines in the drawings are for the purpose of illustrating unclaimed portions of the chair and form no part of the claimed design.
